UNITED STATES PATENT OFFICE

HALSEY MONROE LARTER, OF NEWARK, NEW JERSEY, ASSIGNOR TO WILLIAM S. HICKS' SONS, OF NEWARK, NEW JERSEY

DESIGN FOR A COMBINED GOLF PENCIL AND WRIST STRAP HOLDER

Application filed August 29, 1930. Serial No. 36,824. Term of patent 3½ years.

To all whom it may concern:

Be it known that I, HALSEY MONROE LARTER, a citizen of the United States, and a resident of Newark, in the county of Essex and State of New Jersey, have invented a new, original, and ornamental Design for a Combined Golf Pencil and Wrist Strap Holder, of which the following is a specification, reference being had to the accompanying drawings, forming part thereof.

I claim:

The ornamental design for a combined golf pencil and wrist strap holder, as shown.

HALSEY MONROE LARTER.
